UNITED STATES PATENT OFFICE.

ARTHUR SHERMAN HALSEY, OF WASHINGTON, DISTRICT OF COLUMBIA, ASSIGNOR
TO THE GOVERNMENT OF THE UNITED STATES.

ORDNANCE.

1,369,278.

Specification of Letters Patent. Patented Feb. 22, 1921.

Application filed September 28, 1918. Serial No. 256,033.

To all whom it may concern:

Be it known that I, ARTHUR S. HALSEY, a citizen of the United States, residing at Washington, District of Columbia, have invented new and useful Improvements in Ordnance, of which the following is a specification.

This invention relates to ordnance, and has particular reference to mounts of the type in which the gun may be withdrawn into lowered position when not in use. This type of gun mount, known generally as the "disappearing" mount, is especially adapted for use on submarine vessels, as in this kind of vessel it is desirable, for obvious reasons, to lower the gun into a compartment below the deck when the gun is not in use as, for instance, when the vessel is submerged.

In vessels of the submarine type, the available space within the hull is very restricted and, therefore, it is particularly desirable that the compartment into which the gun and mount are withdrawn may be as small as possible, and to this end, I provide an improved mount, which will require, when lowered, a compartment of minimum size, it being possible to lower the gun and mount into a chamber the depth of which is equal to the diameter of the gun plus the recoil mechanism or to the diameter of the housing for the breech end of the gun and recoil mechanism when those members are inclosed in a fluid tight casing.

When lowering the gun into a compartment, it is necessary that the gun be maintained at the correct angle in a vertical plane so that, as the gun approaches its lowermost limit of travel, it will be, substantially, in parallelism with the bottom of the compartment. Heretofore, it has been customary in mounts of this type to manually change the angle of the gun, preparatory to withdrawal or while it is being lowered, but this manual operation is open to the objections that considerable time is wasted in adjusting the gun preliminary to lowering the same, and not infrequently due to carelessness on the part of the operator or the exigencies of the occasion, the operator does not lower the gun at the right angle, with the result that the lower end of the gun strikes the bottom of the compartment resulting in damage to the gun or vessel. It is an object of the present invention to pro-

vide means for automatically maintaining the gun at the correct vertical angle while the mount is being lowered, thus entirely eliminating the personal factor and insuring against accidents. By automatically changing the vertical angle of the gun relative to the mount while the gun is being lowered, it is not necessary to first bring the gun to the correct vertical angle preparatory to withdrawing the same and, therefore, considerable time is saved and the gun may be immediately and quickly withdrawn into the compartment.

The present invention is designed to embody certain features of construction and a novel combination of parts in a simple and practical disappearing mount which will be entirely reliable and efficient in operation.

The above and other objects of my invention are obtained in the structure described in detail in the following specification, and illustrated in the accompanying drawings, and wherein:

Figure 1 is a side elevational view of the mount with the gun in raised position ready for firing.

Fig. 2. is a view similar to Fig. 1, but illustrates the gun and mount in withdrawn or lowered position and within a compartment.

Fig. 3. is a rear end view of the structure shown in Fig. 1.

Fig. 4. is a top plan view of the gun and mount in raised position.

Fig. 5. is a perspective view of the mount with the yoke in raised position and with the gun slide and other parts of the structure removed.

Fig. 6. is the sectional view through the platform of the mount with the yoke shown in lowered position.

Fig. 7. is a perspective view, partly in section, and partly in elevation, of the gun elevating mechanism, and

Fig. 8. is a sectional view taken longitudinally through one of the cylinders whereby the mount is raised and lowered.

Referring to the drawings, wherein like reference characters represent like parts in several views, 10 designates the usual platform or base which may be of any suitable construction and which, in the present instance, is fixed to the floor of the well or chamber 11 located between the main deck 12 and the superstructure 13. The chamber or well 11 may be provided with a cover 110

comprising a swinging door or pair of doors (not shown) hinged to the superstructure and adapted to be closed over the chamber, when the gun is in lowered position.

5 Rotatably mounted upon the platform 10 is the gun carriage comprising a table plate 14 and a yoke 15, the latter having at its upper ends the usual bearings which receive the trunnions of a cradle or slide 16 in 10 which a gun 17 recoils in a line of fire. To prevent water from gaining access to the bore of the gun and the recoil mechanism, the latter of which comprises a cylinder 18, shown in dotted lines in Fig. 1, the slide 16 15 is extended backwardly to slightly beyond the breech of the gun and houses the rear end of the gun and recoil mechanism. The rear end of the slide is provided with a water-tight door 19 which is removed when charging the gun and to permit the gun to recoil in the slide, when the gun is fired.

The means for training the gun may be of any suitable construction, it being shown, for illustrative purposes, in the present instance, as comprising the well known type of training mechanism having the usual worm gear 20 fixed to the base 10, a worm 21 meshing with the gear 20, a two hand drive wheel 22 and the usual connections 25 between the worm 21 and drive wheel 22 including the vertical shaft 23. The shaft 23 is jointed, as at 24, so that the hand wheel 22 may be lowered when the gun is withdrawn into the chamber 10, as will be 30 explained more in detail.

The table plate 14 has a rectangular opening 25 (Fig. 6) which, when the gun is in the correct azimuth, registers with a similarly shaped recess 26 in the platform 10 to 40 form a well which receives a portion of the yoke 15 when the mount is lowered into withdrawn position. Arising from the table plate 14 and located to each side at the recess 25 therein, is a standard or bracket 27 45 between which extends a transverse shaft 28 upon which is pivoted the yoke 15.

The shaft 28 is located adjacent the forward ends of the bracket 27 so that the rear lower end of the yoke 15 may be lowered into 50 the well 26 within the platform 10, as most clearly shown in Fig. 6. For the purpose of locking the yoke in elevated position, the rear lower ends of the cheeks of the yoke are provided with openings 29, which register 55 with openings 30 in the rear ends of the brackets 27 when the yoke is raised. Within the openings 29 of the yoke are slidably mounted pins or plungers 31 adapted to be moved outwardly, so that their outer ends 60 may be engaged in the openings 30 of the brackets 27 to lock the yoke in elevated position. It is obvious, of course, that, if preferred, the pins 31 may be normally carried by the openings 30 in the brackets and 65 shifted inwardly into the openings 29. Any

suitable means for shifting the pins 31 may be employed, in the present instance, each of the pins being illustrated as having a pair of ears to which hand levers (not shown) may be secured. At the forward end of each bracket 27 is an abutment 32 against which the forward end of the yoke engages and thus swinging movement of the yoke in a forward direction is limited.

In accordance with the present invention, 75 the mount is provided with gun elevating means, which may be manually operated to change the vertical angle or elevation of the gun for purpose of fire, and which may be automatically operated to change the angle 80 between the gun and mount when lowering the gun into the chamber of the vessel. The slide or cradle 16 carries the usual elevating rack or segment 32' and the change in elevation is effected by means of a manually 85 operated element shown, in the present instance, as comprising a two hand drive wheel 33. The connections between the rack 32' and the hand wheel may be of the type now in general use and comprise, as most 90 clearly shown in Fig. 7, a pinion 34 meshing with the rack 32' and carried by a shaft 35 upon the outer end of which is fixed a worm gear 36, meshing with a worm 37 carried by a shaft having a bevel gear 95 38, which in turn meshes with a bevel gear 39 fixed on the same shaft as is the hand wheel 33.

For the purpose of automatically changing the angle of the gun relative to the yoke 100 when the mount is being lowered, means operated by the movement of the yoke is associated with the manually operable elevating mechanism above described and this automatic means comprises, in part, a screw 105 shaft 40 rotatively carried at its lower end in a sleeve 41 and having at its upper end a bevel gear 42 meshing with the bevel gear 39, heretofore referred to. The sleeve 41 is loosely mounted on a horizontally extending 110 rod 42' which is in axial alinement with the shaft 28 upon which the yoke is mounted. Upon the screw shaft 40 is a slide 43 and this slide and the shaft are provided with complementary screw threads so that when 115 the slide is moved longitudinally upon the screw shaft, the latter will be caused to rotate. The slide 43 is maintained against rotation and is caused to travel longitudinally upon the shaft 40, when the latter is swung 120 about its pivot, by means of a link 44 connected at one end to the slide and at its other end to a horizontally extending rod 45 spaced rearwardly of the rod 42'. It will be seen that the screw shaft 40 and the link 125 44 are eccentrically pivoted. The slide has a pair of diametrically opposite longitudinally extending slots 46 and the outer end of the link, which is forked, carries pins 47 130 operating in these slots. By this latter ar-

arrangement operation of the hand wheel 33 for changing the elevation of the gun for purposes of fire may take place.

Any suitable mechanism may be utilized 5 for raising and lowering the mount, but in the present instance, this means is shown as comprising a pair of cylinders 48, located on opposite sides of the mount and each comprising two telescopic parts within 10 which are housed springs 49 which tend to maintain the cylinder in extended condition. Each of the cylinders is pivotally connected at its upper end to the yoke at the point adjacent to the bearings 15 which receive the trunnions of the slide 16, and each is pivotally connected at its lower end to ears 50 carried by the table plate 14, these ears being spaced rearwardly of the line or shaft 28 upon which the yoke 15 is 20 pivoted. When the yoke is lowered into withdrawn position, the parts of the cylinder will telescope into each other due to eccentricity of the pivotal points of the yoke and the cylinders, and when the yoke is 25 moved into raised position, the cylinders will be extended. The pressure of the springs 49 is supplemented by fluid pressure, the fluid pressure being admitted to the cylinders by flexible tubes 51 leading 30 from any suitable pressure device (not shown).

The operation of the structure above described will be readily understood and may be briefly stated as follows: Assuming that 35 the mount is in lowered position, that is in the position shown in Fig. 2; to raise the mount, fluid pressure is admitted to the cylinders 48, whereupon, the cylinders, due to the combined pressure of the springs 49 and 40 the fluid, will be extended and the yoke will be swung forwardly and upwardly about the shaft 28 and into the position shown in Fig. 1. When the mount is in lowered position the portion of gun 17 forward of the 45 slide 16 lies between the cheeks of the yoke 15. As the mount is raised, the slide 43 will move longitudinally upon the shaft 40 and toward the pivot end of the same with the result that the screw shaft 40 is rotated to 50 set into operation the mechanism between the hand wheel 33 and the rack 32', and thus cause the gun to rotate in the bearings of the yoke 15 so that the gun is maintained in a horizontal position. The yoke 24 of the 55 shaft 23 of the training mechanism, the shaft 28 and the rod 42' are all in axial alinement, so that the parts may be simultaneously raised and lowered. After the yoke is raised to its highest position, the 60 pins 31 are moved outwardly and into the openings 30 of the brackets 27. Due to the pin and slot arrangement between the slide 43 and the link 44, the hand wheel 33 may be rotated to elevate the gun for purpose of 65 fire.

The operation of the structure is the reverse of that just described, when the gun is withdrawn from raised position into the chamber of the vessel. In this case the fluid pressure within the cylinders 48 is reduced, 70 the pins 31 having first been withdrawn from the openings 30 in the brackets 27. The fluid pressure within the cylinders is regulated so that the mount is lowered with an easy and steady movement. When the 75 yoke swings downwardly and backwardly, the slide 43 travels outwardly upon the screw shaft 40 causing this shaft to rotate in a reverse direction so that the gun will be maintained in a horizontal plane while the mount 80 is being lowered.

It will be noted from the foregoing description, that the parts of my improved mount are of such relative proportions and disposition that, when the mount is in lowered position, as shown in Fig. 2, the casing or slide 16 housing the breech end of the gun and the recoil mechanism is located within the chamber 11, rearwardly of the base 10 and that the depth of the chamber 11 85 needs be only about equal to the height of this casing to accommodate the entire mount. It will further be seen that with my improved construction, the base 10 and the table plate 14 of the carriage are not pivoted 90 so as to swing downwardly, but these members are fixed in the chamber 11. 95

It is obvious that my invention is susceptible of various modifications and changes which would be within the spirit of the invention without departing from the scope of the following claims.

What I claim is:—

1. In a gun mounting for guns adapted to be raised to firing position, in combination, a base having a recess, a plate rotatably mounted on said base and having an opening adapted to register with said recess, brackets arising from said plate adjacent

said opening and a yoke having a forward portion pivoted at one end of said brackets and a rear portion integral therewith adapted to engage in said recess and opening in lowered position.

2. In a gun mounting for guns adapted to be raised to firing position, in combination, a base having a recess, a plate rotatably mounted on said base and having an opening adapted to register with said recess, brackets arising from said plate adjacent said opening, a yoke having a forward portion pivoted at one end of said brackets and a rear portion integral therewith adapted to engage in said recess and opening in lowered position and means for raising and lowering 120 said yoke.

3. In a gun mounting for guns adapted to be raised to firing position, in combination, a base provided with a central aperture, a plate rotatably mounted on said base having 130

- an opening adapted to register with said aperture, brackets at each side of said opening on said base plate, each provided with two openings, an integrally formed yoke interposed between said brackets having a pin passing through one set of openings to provide a pivotal point and locking means co-acting with the other set of openings and the rear part of said yoke adapted to lock the same in raised position, said openings in the base and plate providing a housing into which the rear of said yoke falls when the gun is in lowered position.
4. In a gun mounting, a horizontally pivoted supporting member, a gun trunnioned therein, and means controlled by the swinging movement of said supporting member for changing the angle between the said member and gun, said means comprising in part a rotatable screw shaft pivotally mounted concentrically to the pivotal line of said supporting member, a slide on said shaft and a connection between said slide and a

point eccentric to the pivotal point of said screw shaft.

5. In a gun mounting, a horizontally pivoted supporting member, a gun trunnioned therein, manually operable means for changing the elevation of the gun for the purpose of fire and having a gear, and a second means associated with said manually operable means and controlled by the swinging movement of said supporting member for automatically changing the angle between the gun and member, said second means comprising a rotatable screw shaft pivoted concentrically to the pivotal line of said supporting member and having a gear meshing with said gear of said first means, a slide threaded on said shaft, and a link between said slide and a point eccentric to the pivoted point of said screw shaft.

Signed at Washington, District of Columbia, this 23rd day of August 1918.

ARTHUR SHERMAN HALSEY.
